UNITED STATES PATENT OFFICE.

MARION WARREN, OF ROCHESTER, NEW YORK.

SAFETY-VALVE.

SPECIFICATION forming part of Letters Patent No. 402,702, dated May 7, 1889.

Application filed July 25, 1888. Serial No. 281,041. (No model.)

To all whom it may concern:

Be it known that I, MARION WARREN, a citizen of the United States, residing at Rochester, in the county of Monroe and State of New York, have invented certain new and useful Improvements in Safety-Valves; and I do declare the following to be a full, clear, and exact description of the invention, such as will enable others skilled in the art to 5 which it appertains to make and use the same, reference being had to the accompanying drawings, and to the letters and figures of reference marked thereon, which form a part of this specification.

15 Safety-valves constructed and adjusted to open at a predetermined pressure often fail after continued use to operate as desired. Several causes tend to affect the desired constancy and uniformity in the action of such 20 valves. Thus the valve, valve-seat, or connected parts may either become worn or be clogged by rust or sediment, and, further, the elasticity of tension-springs may alter or other causes intervene, whereby either a pressure 25 greater or less than that required to open the valve under prior conditions may become necessary. A scale and index therefor normally adapted to indicate the setting of the valve corresponding to a given pressure will there- 30 upon fail to give correct indications, and such scale will require adjustment to the altered condition of the valve before it will correctly indicate the position of said valve correspond- ing to a desired pressure.

35 The object of the present invention is to improve devices for setting the valve for indicating the pressure necessary to open it and for adjusting an indicator-scale to changed conditions in the valve.

40 In the accompanying drawings, Figure 1 represents a vertical section of a device embodying my invention, and Fig. 2 a side elevation of the main part of the same.

The figure of reference 1 denotes a valve- 45 casing provided with an inlet, 2, and an outlet, 3. The inlet and outlet may be located and connected according to the nature of the fluid under pressure and the general use of the apparatus. Between them within the 50 casing is secured a flexible diaphragm, 4, which is firmly held on each side at its pe-

riphery, as indicated. The diaphragm is also held centrally between the nut 6, having a passage, 7, and its seat or counterpart 5, the parts being connected and arranged substantially as shown. The exterior lips of the passage 7 form a valve-seat, 8, for the valve 9. The movement under pressure from the direction of the inlet of that part of the diaphragm not held as above stated acts upon the ring or follower 10, which is connected through arms 11 with the valve-body 12 and tends to open the valve. This body is provided with a stem, 13, and a shoulder, 14. A tension-spring is arranged to bear upon this 65 shoulder, and has a tendency to close the valve in opposition to the fluid-pressure on the opposite side of the diaphragm. The opposite end of the spring has a bearing upon a screw-nut, 15, held against rotation, but not 70 against longitudinal movement, by a feather or projection entering a suitable slot. (Indicated in dotted lines in Fig. 1.) This nut is threaded to engage a screw tube or cylinder, 16, which abuts against the valve-body, and is 75 made hollow to receive the valve-stem. A milled plate or wheel, 17, is secured by a spline or otherwise to this screw-threaded cylinder. The revolution of the wheel 17 turns the cylinder, and by the screw-thread connection of 80 the latter the nut 15, which is held, as before stated, against rotation, is moved longitudinally, so as to increase or decrease the tension of the spring, as desired.

In the face of the milled plate is provided 85 a recess to receive a plate, 18, which is fitted over the cylinder 16 and is provided with a scale. This plate is held in the recess and against the milled wheel by the nut 19, screw-threaded to fit an outer extension of the 90 screw-threaded tube or cylinder 16.

20 denotes a clamp secured upon a ring, 21, which fits the extension 22 of the casing and is fastened thereto by set-screw 23. The object of this clamp is to hold the hand-wheel 95 or plate 17 against rotation. The outer limb of this clamp forms an index for the scale.

24 is a stud or pin fixed in the scale-plate to limit the rotation of the tension-adjusting wheel to one revolution. It is so placed as to 100 engage the index-finger when the latter is situated between the highest and lowest fig-

ures of the scale, these being adjacent to each other.

The scale-plate, above described, when not held by nut 19 is preferably made movable in its seat about the extension of cylinder 16, and its use and operation are as follows: When there may be reason to believe that the scale and index do not correctly indicate the pressure necessary to compress the spring 10 and open the valve, an independent pressure-gage known to be correct is applied so as to communicate with the interior of the casing. In the construction illustrated it may be applied to the branch pipe 25 and the cock 26 15 turned to admit the fluid (or pressure) to the gage temporarily used. The adjusting plate or wheel 17 is next turned to adjust the tension of the spring, so that the particular pressure which opens the valve and allows the fluid to escape is indicated by the gage. The scale-plate is then turned in its seat, so that the index shall point to the mark on said plate denoting the same degree of pressure. This adjustment corrects any variation from 25 the true indication which may have been caused by changes in the apparatus. The scale-plate, after such an adjustment, is secured in proper relative position by any suitable means, as by a jam-nut, 19. Both the 30 hand-plate and scale-plate are then secured in fixed position by means of the clamp 20, except when it is desired to vary the tension of the spring. In case the tension of the spring is very great the use of a key which 35 affords more leverage may be desirable. Such key can be inserted in the angular opening 27, as will be readily understood. The necessity of this could be obviated by making the hand-wheel sufficiently large to afford proper 40 leverage. It is also evident that if the hand-wheel were omitted and the scale-plate placed next the casing the general nature and operation of the device would not be altered, and such arrangement falls within my invention, 45 though the recessed milled plate is preferably used in connection with the valve illustrated in the present instance. It is further obvious that some of the advantages of my improvement would be secured though the scale-plate were not made adjustable, its location 50 and connection being convenient and the construction simple.

Other variations may be made without sacrificing all the advantages of my improvement. For example, the casing, tension device, valve, diaphragm, and connected parts 55 can be varied in form, proportion, and otherwise while retaining an adjustable scale-plate or a scale-plate affixed to the tension-regulating device whether adjustable or not.

The device furnishes means of varying the pressure on a valve from zero to any desired limit by turning the screw-threaded cylinder, and it also provides for the correct adjust-

ment of the scale, so that it shall at any time 65 correctly denote the pressure of a fluid passing through the valve-opening, and it is therefore adapted for use in connection with safety-valves or with valves required to open when the pressure exceeds a desired limit 70 and in connection with fluid-pressure regulators.

Having thus described my invention, what I desire to claim, and secure by Letters Patent, is—

1. The combination of a valve, a tension device to vary the resistance to the opening of the valve, and a movable scale, substantially as set forth, whereby the scale can be adjusted to correctly indicate the desired pressure to open the valve. 75

2. The combination of a valve, a spring tending to close the valve, a movable part to vary the tension of the spring, and a movable scale, substantially as set forth. 80

3. The combination of the valve, the spring, the milled wheel or plate, the screw-threaded cylinder, the longitudinally-movable nut, and the movable scale seated in a recess in the milled head, substantially as set forth. 85

4. The combination of the casing, the valve, the spring, the milled plate, the screw-threaded cylinder, the movable nut on said cylinder, and the clamp, substantially as set forth, whereby the milled plate is held in fixed position after adjustment of tension. 90

5. The combination of the valve, the spring, the milled plate, the screw-threaded cylinder, the longitudinally-movable nut on the cylinder, the movable scale, and the jam-nut for holding the scale against the plate, substantially as set forth. 100

6. The combination of the valve, the spring, the milled plate, the screw-threaded cylinder, the longitudinally-movable nut thereon, the movable scale, the nut for holding the scale against the plate, and the clamp to hold the wheel or plate in fixed position, substantially as set forth. 105

7. In a fluid-pressure-regulating apparatus, a valve, a tension device, and a scale mechanically connected to the tension device, all combined substantially as set forth, whereby the scale is moved by the manipulation of said tension device. 110

8. In combination, in a fluid-pressure-regulating apparatus having a casing, a scale or indicator connected to a tension device, a valve adapted to close and disclose a passage for a fluid, and a branch pipe communicating with the interior of the casing to receive a pressure-gage, substantially as set forth. 115

In testimony whereof I affix my signature in presence of two witnesses.

MARION WARREN.
